FLUID MINING OF UNDERGROUND
ORE DEPOSITS

Joseph N. Pew III, Gladwyne, Pa., assignor to General Crude Oil Company, Houston, Tex., a corporation of Delaware

Filed Sept. 2, 1960, Ser. No. 53,678
7 Claims. (Cl. 262—1)

This invention relates to the mining of underground ore deposits by erosion thereof with fluids and more particularly by injecting air and water through a pipe extending into the deposit and carrying means adapted to loosen ore particles from the deposit wall.

Mining of ore deposits, such as phosphate rock, conventionally is done by loosening the deposits by mechanical means or explosives and transporting the ore particles in dry form from the mine. In cases where the deposits are relatively shallow, e.g. 50-200 feet beneath the surface, strip mining is often practiced by removing the overburden to provide access to the ore. The removal of many tons of earth overlying the deposit, however, is a costly procedure. Proposals have been made heretofore to utilize erosion of the deposit by water as a means of mining but none of these appears to have been successful except in cases where the deposit is composed of water soluble material such as rock salt.

The present invention provides an effective method for fluid mining of ore deposits which are not water soluble. The process is particularly useful in the mining of phosphate rock. The invention also embraces the combination of apparatus for practicing the process.

According to the invention a borehole is drilled from the ground surface into the ore deposit and a casing is set in the hole with its lower end terminating at an upper part of the deposit. A fluid inlet pipe of smaller diameter is positioned within the casing to form therewith an annulus which serves as a fluid outlet. A tough flexible hose is attached to the bottom of the pipe preferably through a swivel joint. The hose is of sufficient length that at least a substantial part of it can contact the deposit wall during operation of the process. Water and air are pumped down the pipe and a high rate of fluid flow is maintained such that passage of the fluids from the hose causes the hose to move or flap vigorously, thus beating against the deposit wall. The blast of water and air against the deposit together with this beating action of the hose readily loosens the deposits. The loosened particles are suspended in the fluid and carried up the annulus and out of the casing with it. The mixture is then sent to suitable separating means for removing the ore particles from the water. If desired, the separated water can be recycled in the process.

Another feature of the invention involves the use of a plurality of cleats or lugs made of hard material such as steel and attached in suitable fashion to the flexible hose. As the hose beats against the deposit, the cleats cut into the ore and increase the rate at which it is loosened.

Still another feature of the invention involves the introduction into the hole in the deposit of pieces of a hard solid material preferably having sharp edges. The material is selected with respect to particle size and density such that movement of the fluid in the hole causes contact between the particles and the deposit wall but the particles are not transported by the fluid up the casing annulus. The contact between the particles and the deposit further enhances the rate of erosion. For this purpose small chunks of metal, hard rock or the like, can be used. By way of illustration but not in limitation of this feature of the invention, steel blocks having dimensions

2

of one-quarter to three inches can be employed. The appropriate dimensions of the abrading chunks will depend upon the density of the material and the velocity of the fluids passing through the hole.

The invention is more specifically illustrated in the accompanying drawing which diagrammatically shows a borehole extending to a bed of ore and the arrangement of apparatus used in practicing the invention.

Referring to the drawing, numeral 10 represents the ground level and 11 is a casing positioned in a borehole which has been drilled into the bed of ore. A pipe 12 centered within the casing is secured to a flange 13 which closes the annulus at the top of the casing. Pipe 12 is connected to water line indicated schematically at 14 and provided with water pump 15 and also to air line 16 having blower 17. A fluid outlet line 23 leads from casing 11 to a separator (not shown) adapted to remove the ore from the water.

The lower end of pipe 12 preferably is provided with a swivel joint 18 to which is attached a tough flexible hose 19 constructed, for example, from neoprene rubber. Hose 19 is of such a length that a substantial part of it can abut against the wall 20 of the deposit. The hose preferably is provided with a plurality of cleats 21 carried by metal bands 22 secured to the hose.

In conducting the mining operation, water and air are pumped at high rates through line 12. Exit of the fluid from the end of hose 19 causes it to flap vigorously against the deposit wall 20. Impingement of the fluid mixture on the wall together with this flapping action loosens the deposit, and the ore particles are carried by the fluid mixture up the casing annulus and out through pipe 23. From time to time as the hole in the ore bed gets larger, pipe 12 can be removed from the hole and hose 19 can be replaced by a longer hose so that effective mining of the ore can be continued.

I claim:

1. Apparatus for mining an underground ore deposit comprising, in combination, a casing extending from ground level to the deposit, a fluid inlet pipe positioned within the casing and forming an annulus therewith, closure means for the annulus at the top of the casing, a tough flexible hose positioned within the deposit and connected to the bottom of said pipe, said hose having a flexibility and length such that it is capable of flapping against the wall of said deposit, means for introducing air and water into said pipe at rates such that the flow of the mixture thereof out of said hose effects vigorous movement of the hose in contact with the deposit and means for withdrawing fluid carrying loosened ore particles from the upper part of said annulus.

2. Apparatus according to claim 1 also including a plurality of cleats attached to said hose to aid the loosening of the ore from the deposit.

3. Apparatus according to claim 2 also including a swivel joint between the bottom of the pipe and the flexible hose.

4. Apparatus according to claim 1 also including a swivel joint between the bottom of the pipe and the flexible hose.

5. Method of mining ore from an underground deposit which comprises drilling a borehole extending into the deposit, positioning a casing in the borehole with its lower end terminating in an upper part of the deposit and a pipe within the casing forming an annulus therewith and attached at its lower end to a tough flexible hose positioned in an uncased portion of the hole, said hose having a flexibility and length such that it is capable of flapping against the wall of said deposit, pumping air and water downwardly through the pipe at a rate such that the passage of the fluids from the hose effects vigorous movement there-

of against the wall of the deposit, whereby particles of ore are loosened from the deposit, and withdrawing fluid carrying loosened ore particles from the upper part of said annulus.

6. Method according to claim 5 also comprising introducing into the hole in the deposit a relatively hard particulate solid material having a particle size and density such that movement of the fluid causes contact between the particles and the deposit wall without transport of the particles up the annulus, whereby erosion of the 10 deposit is enhanced.

7. Method according to claim 5 wherein the ore deposit is phosphate rock.
